ART OF CRACKING HYDROCARBONS

Edward W. Isom, Scarsdale, N. Y., and Eugene C. Herthel, Chicago, Ill., assignors to Sinclair Refining Company, New York, N. Y., a corporation of Maine

Application June 12, 1929, Serial No. 370,281

2 Claims. (Cl. 196—58)

This invention relates to improvements in the manufacture of lower boiling hydrocarbon oils, such as gasoline, from higher boiling hydrocarbon oils, such as gas oil, crude oil and reduced 5 crude oil.

The present invention provides an improved method of cracking higher boiling hydrocarbon oils in which high boiling oil is heated to a high cracking temperature, upwards of about 900° F., 10 under superatmospheric pressure to produce a high yield of gasoline in a single passage as a stream of high velocity through a heating operation, in which the hot oil products from the heating operation are suddenly cooled by direct heat 15 exchange with introduced cooler high boiling oil to arrest objectionable reaction prior to separation, following expansion, of vaporized components and residual components of these hot oil products, and in which the hot oil products from 20 the heating operation prior to such cooling are passed in brief indirect heat exchanging relation with residual components separated from the cooled oil mixture to assist in cooling the hot oil products from the heating operation and to 25 promote complete separation of low boiling components from the residual oil mixture.

According to the present invention, a flowing stream of high boiling oil is heated to a high cracking temperature under superatmospheric 30 pressure, the total stream of hot oil products from the heating operation is passed under maintained superatmospheric pressure in indirect heat exchanging relation with a body of residual oil in a vapor separating receptacle, the pressure on the 35 stream of hot oil products from the heating operation is then reduced and they are released under reduced pressure within the vapor separating receptacle, a stream of cooler high boiling oil is introduced into the stream of hot oil products 40 from the heating operation before these hot oil products are released within the vapor separating receptacle but after the heat exchange with the body of residual oil therein, vapors including vapors of the desired low boiling oil are taken off 45 from the vapor separating receptacle but after the heat exchange with the body of residual oil therein, and residual oil is discharged from the vapor separating receptacle. The vapors taken off from the vapor separating receptacle may be 50 subjected to any suitable condensing or fractionating and condensing or other recovery operation.

The invention will be further described in connection with the accompanying drawing which 55 illustrates, diagrammatically and conventionally,

in elevation and partly in section and with parts broken away, one form of apparatus adapted for carrying out the invention.

In carrying out the invention in the apparatus illustrated, high boiling oil, gas oil for example, 60 is forced, as a stream, through the heating conduit 1 in the heating furnace 2, the heat exchange coil 3 and the pressure regulating and reducing valve 4, successively, into the vapor separating receptacle 5 by means of pump 6; the high boiling oil is heated to a high cracking temperature, 900—950° F. for example, under superatmospheric pressure, 300—600 pounds per square inch as discharged from the heating conduit for 65 example, maintained and regulated by means of valve 4, in the heating conduit 1; the pressure on the stream of hot oil products discharged from the heating conduit is reduced at the valve 4, to a pressure approximating atmospheric pressure but sufficient to maintain flow through the 70 rest of the apparatus for example; relatively cool high boiling oil, gas oil, crude oil or reduced crude oil, or a high boiling oil fraction produced in the operation for example, is introduced into the stream of hot oil products passing from the heat exchange coil 3 to the vapor separating receptacle 75 5 through connection 7; vapors, including vaporized components of the hot oil products discharged from the heating conduit and any vaporized components of the introduced cooling oil, 80 separate from residual oil in the vapor separating receptacle 5 and escape through connection 9, to recovery apparatus for the separation and condensation of the low boiling oil product, gasoline 85 for example; and a body of this residual oil is maintained in the lower end of vapor separating receptacle 5 normally submerging the heat exchange coil 3 from which residual oil is discharged through connection 10 as the operation 90 proceeds. The cooling high boiling oil may be introduced into the stream of hot oil products discharged from the heating conduit either before or after the reduction of pressure thereon, although the latter scheme of operation is usually more advantageous, but this cooling high 95 boiling oil is introduced into the hot oil products discharged from the heating conduit after they have passed through the heat exchange coil 3 and before they are released within the vapor separating receptacle 5. The rate of introduction of cooling high boiling oil may be regulated to make the temperature of the resulting oil mixture so low that further reaction of the hot oil products discharged from the heating conduit 1 is arrested, although high enough to involve cracking 100 105 110

of components of the introduced cooling oil, or so low as to inhibit any cracking of any components of the resulting oil mixture; the temperature of the body of residual oil in the lower end 5 of the vapor separating receptacle 5 may be maintained in the range approximating 700-800° F. or in a range approximating 600-700° F. for example. The heat exchange coil 3 is advantageously arranged so that the path of travel there- 10 through for the hot oil products discharged from the heating conduit is short to minimize the period of time over which these hot oil products are subjected to cooling by this indirect heat ex- change. In the apparatus illustrated, the cooling 15 high boiling oil is introduced through connection 7 in intimate mixture with the hot oil products discharged from the heating conduit. This cooling high boiling oil must be supplied through connection 7 at a temperature lower than that at 20 which the hot oil products from the heating conduit enter connection 8, but it may be used, before being so supplied through connection 7, as a cooling medium in heat recovery heat ex- 25 changers, and so preheated to temperatures as high as 600° F. or higher prior to introduction into the hot oil products discharged from the heating conduit.

In initiating operation in the apparatus illus- 30 trated, high boiling oil is circulated from the vapor separating receptacle 5 through the heating conduit 1 back to the vapor separating receptacle 5 by means of pump 6 and connection 11, valve 12 in connection 11, however, being closed during normal operation. During normal opera- 35 tion, residual oil discharged from the vapor separating receptacle 5 through connection 10 is dis- charged through cooler 13 and connection 14.

The vapors escaping from the upper end of the vapor separating receptacle 5 through con- 40 nection 9 are discharged into the lower end of fractionating tower 15. This fractionating tower may, for example, be of conventional "bubble" tower construction. The vapors remaining un- 45 condensed escape from the upper end of frac- tionating tower 15 through connection 16 to con- denser 17 arranged to discharge into the receiver 18 from which condensate is discharged through connection 19 and uncondensed vapors and gases through connection 20. The operation of the 50 fractionating tower may be controlled, or in part controlled, by the regulated introduction of a part of the condensate collected in receiver 18, or some similar low boiling fraction, into the upper end of the tower through connection 21 by means of pump 22. The operation of the 55 fractionating tower 15 may also be controlled, in part, by the regulated introduction of raw high boiling oil into the tower at an intermediate point through connection 23 by means of pump 24. The operation of the fractionating tower 15 may also be controlled by regulated circulation of relatively cool high boiling oil through the heat exchange coil 25 by means of pump 26. An intermediate fraction may be discharged as a con- 60 densate from the fractionating tower 15 at an intermediate point through connection 27. The apparatus illustrated is arranged to provide for return to the fractionating tower 15 of vapors entrained in such discharged condensate or sep- 65 arated therefrom by the maintenance of a some- what lower pressure in the separator 28 than prevails in the fractionating tower 15 at the point from which the condensate is discharged, from separator 28 through connection 29. Any inter- 70 mediate fraction so discharged is discharged from 75

the separator 28 through cooler 30 and connec- 80 tion 31. The highest boiling oil separated in the fractionating tower 15 may be forced through the heating conduit 1, together with any raw high boiling oil supplied through connection 23 or connec- 85 tion 32, by means of pump 6 through connec- 90 tions 33 and 34, or this fraction or part of it may be discharged through cooler 35 and connec- 95 tion 36 or connection 37. The high boiling oil supplied to the heating conduit 1 by means of pump 6 may consist exclusively of a conden- 100 sate fraction separated in the fractionating tower 15 or of raw oil supplied through connection 32, or it may comprise a mixture including such a condensate fraction and raw oil.

The cooling high boiling oil supplied through connection 7 may consist either of raw high boil- 105 ing oil, such as crude oil or reduced crude oil, supplied through heat exchange coil 25 and connec- 110 tion 38, or of raw high boiling oil, such as gas oil or crude oil or reduced crude oil, supplied through connections 36, 37 and 39, or of a condensate fraction supplied from the lower end of fractionating tower 15 through cooler 35 and connec- 115 tions 37 and 39, or of any mixture of such oils or oil fractions.

The coolers 13, 35 and 30, or such of these cool- 120 ers as are utilized in carrying out the invention in apparatus such as that illustrated, may consist of heat exchangers in which oil to be processed or undergoing processing in the operation of the present invention or in some other operation is used as a cooling medium, or some extraneous cooling medium, water for example, may be used as a cooling medium in these coolers.

In the apparatus illustrated, the vapor separat- 125 ing receptacle 5, the fractionating tower 15, and connections 7, 8, 9, 33, 34 and 38 are with ad- 130 vantage thoroughly lagged or thermally insulated.

In the improved method of operation provided by the present invention, any tendency toward entrainment of low boiling, or intermediate boil- 135 ing, components, entrained or dissolved, in the residual oil discharged from the vapor separat- 140 ing receptacle is reduced to a minimum, although this residual oil includes not only very high boil- 145 ing components of the hot oil products dis- charged from the heating operation but also any very high boiling components of the cooling high boiling oil introduced into these hot oil products dis- charged from the heating operation, by means of a heat exchange which assists in cooling, or in initiating the cooling, of the hot oil products dis- charged from the heating operation but which heat exchange, limited by the temperature differ- 150 ential between the two media involved as well as by the brief period of heat exchange preced- 155 ing immediate further cooling of the hot oil prod- 160 ucts by direct heat exchange with the introduced cooling oil, need not involve any objectionable further reaction of the hot oil products dis- 165 charged from the heating operation. Any tendency to- 170 ward deposition of carbon or pitch from the hot oil products discharged from the heating opera- 175 tion during this heat exchange, in the heat ex- 180 change coil 3 in the apparatus illustrated, is mini- 185 mized in the improved operation of the present invention by maintaining pressure on these hot oil products through this heat exchange.

At the end of a run, the heating conduit 1 is pumped out and steamed out by means of connec- 190 tion 40.

We claim:

1. In the manufacture of lower boiling hydro-

carbon oils from higher boiling hydrocarbon oils, the improvement which comprises heating a flowing stream of high boiling oil to a high cracking temperature in excess of approximately 900° F. under superatmospheric pressure and producing a high yield of gasoline in a single passage through the heating operation, passing the total stream of hot oil products from said heating operation under maintained superatmospheric pressure in indirect heat exchanging relation with a body of residual oil in a vapor separating receptacle and thereby transferring a substantial quantity of heat from the stream of hot oil products to the body of oil in the vapor separating receptacle and promoting a more complete separation of low boiling components from the residual oil mixture, thereafter materially reducing the pressure on said stream of hot oil products and releasing them under materially reduced pressure within said vapor separating receptacle, introducing a stream of cooler high boiling oil into said stream of hot oil products from said heating operation before they are released within said vapor separating receptacle and after said heat exchange with the body of residual oil therein in sufficient quantity to arrest cracking of the hot oil products discharged from said heating operation, and taking off vapors including vapors of the desired low boiling oil from said vapor separating receptacle and discharging residual oil therefrom.

2. In the manufacture of lower boiling hydrocarbon oils from higher boiling hydrocarbon oils, the improvement which comprises heating a flowing stream of high boiling oil to a high cracking temperature in excess of approximately 900° F. under superatmospheric pressure and producing a high yield of gasoline in a single passage through the heating operation, passing the total stream of hot oil products from said heating operation under maintained superatmospheric pressure in indirect heat exchanging relation with a body of residual oil in a vapor separating receptacle and thereby vaporizing from said body of residual oil substantially all of the oil components boiling below about 600° F., thereafter reducing the pressure on said stream of hot oil products and releasing them under reduced pressure within said vapor separating receptacle, introducing a stream of cooler high boiling oil into said stream of hot oil products from said heating operation before they are released within said vapor separating receptacle and after said heat exchange with the body of residual oil therein, and taking off vapors including vapors of the desired low boiling oil from said vapor separating receptacle and discharging residual oil therefrom.
